SEAT SILL

Martin P. Blomberg, Chicago, Ill., assignor to
 Pullman-Standard Car Manufacturing Company, Chicago, Ill., a corporation of Delaware

Application July 16, 1934, Serial No. 735,361

3 Claims. (Cl. 105—397)

This invention relates to railway cars, or similar vehicles, and has for its principal object to provide a longitudinal framing member for interiorly connecting the side posts, the member being of such shape that not only is the entire car body stiffened, particularly against side impact, but in addition, the member provides a convenient support and place of anchorage for the seat pedestals.

10 Further and other objects and advantages will become apparent as the disclosure proceeds and the description is read in conjunction with the accompanying drawing, in which

Fig. 1 is a perspective view more or less diagrammatic of body framework illustrating the car frame to which the seats, seat sills and seat stringers are adapted to be applied.

Fig. 2 is a fragmentary, sectional view taken through the car body;

20 Fig. 3 is a perspective view of the seat pedestal mounting, the seat sill being shown spaced from the seat stringer for the purpose of clarity;

Fig. 4 is a fragmentary, perspective view showing the application of the interior finish to the 25 belt rail;

Fig. 5 is a fragmentary, sectional view showing the manner in which the interior finish is applied to the seat sill and seat stringer.

But this specific illustration is for the purpose 30 of disclosure only and the appended claims should be construed as broadly as the prior art will permit.

In the illustrative embodiment of the invention, the car framework consists of a center sill 10, 35 end sills 11 and 12 secured to opposite ends of the center sill, door end posts 13 and 14, and 15 and 16, rising from the end sills 11 and 12, respectively, top anti-telescoping plates 17 and 18, which rest upon the door end posts, and top sills

40 19 and 20 supported by the end posts and connected at the top and bottom by plates 21 and 22 which with the top sills form a box girder extending from one end of the car to the other. All of these structural members are preferably made of aluminum alloy, and together constitute the main framework of the car.

The shell of the car is formed by a plurality of curved ribs 23 which extend from the top 50 sills 19 and 20 to the upper portion of the center sill 10. The ribs lie in vertical planes and are connected together by various longitudinal framing members, such as a roof stringer 24, a window header stringer 25, a belt rail 26, a seat 55 stringer 27, a seat sill generally designated 28,

a side sill 29, and a plurality of floor stringers including an inverted channel 30.

The belly of the car is formed by arcuate bars 31 which extend from the side sills 29 to the bottom of the center sill 10. These bars are 5 strengthened by struts 32 and 33.

A metal skin 34 is applied to the exterior of the skeleton framework, as shown in Figs. 2 and 4.

The seat sills 28 are preferably formed in one piece and when made of aluminum alloy, the 10 extrusion process of fabrication is preferably employed. The seat sills, however, as well as the other structural members, may be made of high tensile steel, or other suitable material, and certain objects of this invention are achieved even 15 when the seat sills are made in more than one piece.

The seat stringers in the embodiment of the invention shown have top and bottom flanges 35 and 36, respectively, which are adapted to be riveted or otherwise secured to the side posts or ribs 23, and the intermediate portion of the stringer consists of steps 37 and 38, the latter being flanked at the bottom by a stub flange 39.

Seat sills 28 nest with the seat stringers 27 and 25 each comprises a bottom angle portion consisting of a vertical flange 40, a horizontal flange 41, and an inwardly extending offset or U-shape portion 42 having a longitudinal flange 43 offset from the flange 40 which mates with the groove formed 30 by the step 38 of the seat stringer and the stub flange 39 which flanks it. The flange 40 of the seat sill is secured to the side posts or ribs 23 by rivets or other suitable means, and rivets 44 fasten the seat sills to the seat stringers. It will be 35 observed that very little shear is placed on the rivets 44 due to the interlocking tongue and groove joint between the seat sills and the seat stringers.

The combination of the seat sill and the seat 40 stringer, interlocked as they are, forms a rigid girder which is capable not only of resisting vertical bending but also horizontal bending. The resistance to horizontal bending is particularly important in case an object strikes the side of the 45 car.

The interior finish consisting of a sheet 45 of plywood, or other suitable material, fits against the vertical web 42 of the seat sill and the step 50 37 of the seat stringer, and is secured in place by machine screws 46. At the top, the finish is secured to the belt rail 26, the latter being provided with a longitudinal inset 47 so that the finish sheet is flush with the belt rail (Fig. 4). The window sill is indicated at 48.

The horizontal flange 41 of the seat sill forms a ledge upon which the seat pedestals 49 are conveniently supported and secured in place. The pedestals may be of any suitable type and are here shown as T-shaped and hollow, the leg portion 50 being secured to the floor channel 30 by brackets 51 and 52. The arm 53 of the pedestal rests upon the ledge 41 and abuts the finish sheet 45 (Fig. 5). It is secured to the ledge by rivets 10 54, or other suitable means.

A bottom finish sheet 55 covers the portion of the car structure below the seat sills.

What I claim is:—

1. In a car having a side wall structure, a seat 15 stringer, a seat sill having an interlocking horizontally arranged tongue and groove joint with the seat stringer for forming a rigid girder extending lengthwise of the car at the sides thereof for resisting lateral bending of the side walls 20 of the car, said sill including a web and an inwardly extending flange, said flange being adapted to support the outer end of a seat pedestal and said sill and stringers being rigidly connected to said side wall structure.

25 2. In a car having upstanding ribs at the sides

thereof, a seat stringer member adapted to be attached to the ribs of said car and extend along one side thereof, a seat sill member having a ledge thereon for supporting the outer end of a seat, one of said members having a groove extending longitudinally thereof and the other a tongue for engaging said groove, and means extending through said members for connecting the same together with said tongue in said groove whereby shearing of said means is prevented when weight is applied to said seat.

3. In a car having a side wall comprising a plurality of side posts, the combination of a seat stringer and a seat sill, said sill and stringer having attaching flanges adapted to be attached to said posts, and having offset interconnecting portions for resisting the inward bending of said wall, means for connecting said sill to said stringer for holding said offset interconnecting portions interengaged whereby said means will be relieved of shearing stress when weight is applied to said sill, and means integral with said seat sill for supporting the outer end of a seat from said sill.
